UNITED STATES PATENT OFFICE

CHARLES EDWIN HAMILTON, SR., OF HOLLYWOOD, CALIFORNIA, ASSIGNOR TO EDWIN LANE, PERCY MENDELSON, AND CHARLES MENDELSON, ALL OF NEW YORK, N. Y.

FLATWORK IRONER

Application filed January 20, 1930. Serial No. 421,892.

The invention relates to laundry and dry cleaner machinery, more especially to so-called flat work ironers of either the chest or cylinder type of ironer.

5 It has for its object means for directing the work leaving one roll to the succeeding roll, and more especially to eliminate the unsightly string marks from the work, being particularly adaptable to laundry machinery wherein the work is stripped from the rolls by suitable flexible stripper devices, for example, in the manner more particularly set forth in my Patent 1,867,741 granted to me July 19, 1932. Through the use of such 10 stripper devices no string marks are present in the finished work even when strings or the like are employed in connection with the first roll—all traces thereof being obliterated by the action of the subsequent rolls.

15 A further object of the invention resides in means to enhance the effectiveness of operation of the machinery by preventing the work from rising unduly in the space between the successive rolls of the ironer, and thus obviate temporary shut-downs and work "turn-backs". The invention is more particularly 20 adaptable to ironing machines in which provision has been made for preventing the dropping down or backwardly from a roll 25 of its cover cloth which is lapped thereon, for example, by means of guard members and in the manner set forth in my aforesaid patent.

In carrying out the invention, there is associated with the usual rolls of a flat-work ironer, provided with suitable guard or binder members located longitudinally thereof at required intervals and bearing both on the feed and delivery sides of a roll to insure the 30 retention of a cover cloth firmly thereon as well as to prevent said cover cloth from dropping down or backwardly, extensions or 35 guide toes or like members arranged to project outwardly from these guard or binder members both at the feed side of a roll and at its delivery side.

These guide toes are bowed to conform to the steam chest periphery and are adapted to engage with the work fed to a roll as it issues 40 therefrom in the event of its rising beyond

a predetermined distance, as well as serving to assist in the progress of the work between rolls. The said guide toes, moreover, are arranged to yield in case of unavoidable jam, either through their inherent elasticity or 45 that of a carrying guard member or in being flexibly or hingedly connected therewith.

The nature of the invention, however, will best be understood when described in connection with the accompanying drawings, in 50 which:

Fig. 1 is a fragmentary plan view of a flat work ironer equipped with the novel work-directing means.

Fig. 2 is a fragmentary vertical section 55 taken on the line 2—2, Fig. 1 of the drawings, and on an enlarged scale.

Fig. 3 is a fragmentary longitudinal section through a flat work ironer and illustrates the application of the novel guiding 60 members thereto.

Fig. 4 is an enlarged vertical section 65 through a roll and combined guard and guide member, with portion of work passing therethrough in the direction indicated by 70 75 the arrows.

Referring to the drawings, the invention is illustrated, by way of example, as applied to an ironing machine of the chest type having a plurality of ironing rolls 10 which are 80 adapted to iron flat work, such as bed and table linen, etc. The said rolls to this end are journaled for rotation above a steam-heated chest 11, the surface of which immediately beneath each roll is generally concave 85 to secure greater ironing contact. No claim is made to the apparatus per se, the same being of any well-known or special design and provided with standard mechanism (not shown) for rotating the individual rolls. 90

These rolls are covered with a cloth covering 12, usually hair padding, wool padding or matted padding which is frictionally held thereon by being wound thereover with lapped portion 13 to insure retention of 95 the cover on the roll surface. Said cover cloth, particularly at the lapped portion 13, has a tendency to work away from the underlying cloth portion on the return travel; and provision has been made, in the application 100

of suitable guard or binder members 14 thereto, to prevent this breaking away and doubling over, as is more fully set forth in my said Patent 1,867,741.

- 5 These guard members are associated with the individual rolls, as shown, and extend over substantially the exposed portion of a roll to bear both upon the feed and delivery sides thereof, serving to retain the cover 10 cloths thereon, and are disposed longitudinally of a roll preferably equidistantly at the required intervals.

As a convenient means of thus positioning the various guard members, brackets 15 extend longitudinally over the ends of a roll, being secured to the side frame pieces 16 of the ironing machine; and the said brackets support also a hollow triangular holding member 17 positioned over a roll parallel to 20 its longitudinal axis and held to the respective brackets by means of upright supports or posts 18 screwed thereto and beveled at the top. The side walls of member 17 are brought together over said beveled portion and are 25 secured at their upper edges to close the member, as by riveting. Angle pieces 19, furthermore, are attached to the underside of the member 17 to hold between their downwardly directed sides, as by means of a cotter pin 30 20, an upwardly-turned slotted spur 21 of supports 22 to which the guard members are welded. The said guard members, moreover, are preferably of resilient material and more 35 or less semi-circular in form to cover substantially the exposed portion of the roll with which they coat.

Stripper members 23 are also shown associated with a roll, on the delivery side thereof, to strip from them the work 24 as it passes from one roll to the next, all of which is more particularly set forth in my aforesaid patent. These stripper fingers may conveniently be secured by notching the inner ends thereof 45 as at 25 and inserting the same through corresponding slots 26 in the corresponding side of the hollow holding member 17.

In the operation of flat work ironers in which the usual endless work-conveying members, as cords or tapes, are dispensed with in whole or in part and stripper members, as the fingers 23, substituted therefor, there may be a tendency for the work to rise 50 between rolls above the surface of the steam chest, for example, as indicated in Fig. 4 of the drawings, and particularly at the feed side of a roll.

In accordance with the invention there are, 60 therefore, provided guide toes 30 at the feed side of a roll, which toes may be associated with the corresponding guard members 14 either integrally or in being hingedly secured thereto; and the same are designed to yield 65 under sufficient pressure as in being inherent-

ly flexible or flexibly or hingedly connected with the corresponding guard member.

For example, the end of a guard member at the feed side may be continued substantially horizontally outwardly over the steam chest 70 periphery and curved to conform substantially thereto, the extreme outer portion of the extension being turned over, as at 31, to afford a smooth edge. It is preferred, also, to provide a corresponding projecting portion or toe 32 at the delivery end of a guard member, in accordance with the arrangement set forth in my aforesaid patent, and the projecting toe from the guard member of one roll is then arranged to coact with the corresponding projecting toe member of the succeeding roll to substantially bridge the intervening space, as is more clearly set forth in Fig. 3 of the drawings. These coacting toes are arranged, preferably, to then lie adjacently each other and the one on the feed side slightly above the plane of the coacting toe to avoid obstructing the flow of the work, and thus serve, also, to limit the rise of work passing from one roll to the next and guiding it 90 thereto if required, being displaced from the chest surface a distance to permit normally the work to pass freely from roll to roll.

By the foregoing expedient, the effectiveness of the operation of the ironer is greatly enhanced in that shut-downs and "turn-backs" are obviated; and the arrangement is particularly suitable for use in laundry and dry cleaner machinery not provided with the usual endless work-conveying cords or 100 tapes, being thus especially adaptable to machinery equipped with flexible work-stripping fingers.

I claim:

1. In a flat work ironer, including a succession of ironing rolls with lapped cover cloth: guard members associated with the individual rolls, extending over substantially the exposed portion of a roll and bearing upon both the feed and delivery sides thereof to retain its cover cloth thereon, and yieldable guide toes associated with the respective guard members and extending substantially horizontally therefrom over a portion only of the intervening roll space at the feed side of a roll 110 and at the delivery side thereof, the toes of successive roll guards coacting to bridge the intervening space between the successive rolls for limiting the rise of work therebetween.

2. In a flat work ironer, including a succession of ironing rolls with lapped cover cloth: guard members associated with the individual rolls, extending over substantially the exposed portion of a roll and bearing upon both the feed and delivery sides thereof to retain its cover cloth thereon, and yieldable guide toes associated with the respective guard members and extending substantially horizontally therefrom over a portion only of the intervening roll space at the feed side 120 125 130

of a roll and at the delivery side thereof, the
toes of successive roll guards coacting to
bridge the intervening space between the suc-
cessive rolls for limiting the rise of work
therebetween and the toe on the feed side of
a roll being slightly above its coacting toe.

5 In testimony whereof I affix my signature.

CHARLES EDWIN HAMILTON, SR.
